(57) **CLAIM**

The ornamental design for a spoon rest, as shown and described.

DESCRIPTION

FIG. 1 is a top perspective view of a spoon rest, shown with a support in a raised position, showing our new design; FIG. 2 is a front elevation view of FIG. 1; FIG. 3 is a rear elevation view of FIG. 1; FIG. 4 is a right side elevation view of FIG. 1; FIG. 5 is a left side elevation view of FIG. 1; FIG. 6 is a top plan view of FIG. 1; FIG. 7 is a bottom plan view of FIG. 1; FIG. 8 is a cross-sectional view taken along line 8-8 of FIG. 2;

FIG. 9 is a top perspective view of a spoon rest, shown with the support in a folded position; FIG. 10 is a front elevation view of FIG. 9; FIG. 11 is a rear elevation view of FIG. 9; FIG. 12 is a right side elevation view of FIG. 9; FIG. 13 is a left side elevation view of FIG. 9; FIG. 14 is a top plan view of FIG. 9; FIG. 15 is a bottom plan view of FIG. 9; and, FIG. 16 is a cross-sectional view taken along line 16-16 of FIG. 10.

The broken lines in the drawings depict portions of the spoon rest that form no part of the claimed design.
